PULSE GROUP SYSTEM OF
COMMUNICATIONS

Claud E. Cleton, Washington, D. C.

Application October 11, 1940, Serial No. 360,806

37 Claims. (Cl. 250—8)

(Granted under the act of March 3, 1883, as
amended April 30, 1928; 370 O. G. 757)

1

This invention relates to a system of communication in which the dots and dashes of conventional telegraphic code, hereafter termed signal elements, are transmitted by groups of pulses at the beginning and end of each signal element.

It is an object of this invention to provide means for transmitting a predetermined arrangement of pulses at the beginning of a signal element and then another arrangement at the end of such element.

It is also an object of this invention to provide receiving means that will respond to the group of pulses denoting the beginning of a signal element by starting an audio or other discernible signal indication and terminate the same upon reception of the pulse arrangement marking the end of the signal element.

The foregoing and other objects are realized by the apparatus shown in the drawings wherein:

Fig. 1 is a schematic diagram of a transmitting system for sending two pulses at the beginning of a signal element and one pulse at the end thereof;

Fig. 2 is a schematic representation of a system whereby three pulses are sent at the beginning of a signal element and two pulses at the end thereof; and

Fig. 3 discloses a receiving circuit suitable for responding to the signals transmitted by apparatus as shown in Fig. 1.

The system disclosed herein has a great advantage over the conventional system of transmitting code in that the peak power during the pulses may be many times the average power the transmitter is capable of handling continuously. This increases the reliability of code transmission under poor transmitting conditions. Further, the present system requires no special type of key and the duration of the signal element at the receiver is determined by the length of time the key of the transmitter is held closed.

Referring now to Fig. 1, the tubes 4 and 5 have their respective anodes 6 and 7 connected to the positive plate supply 8 through respective anode resistors 9 and 10. The grids 11 and 12 are connected to negative bias lead 13 through resistors 14 and 15. The grid 11 is also connected to anode 7 through resistor 16 and capacitor 17 in parallel with each other and grid 12 is likewise connected to anode 6 through resistor 18 and capacitor 19 in parallel. Cathode 20 of tube 4 is connected to ground while cathode 21 of tube 5 is normally open circuited through the key 22.

Resistor 14 is two or more times as great as

2

resistor 15 and consequently the potentiometer effect of resistors 18 and 14 is such that when key 22 is closed the tube 5 becomes conducting and tube 4 is made non-conducting but so long as the key 22 is open the tube 4 will conduct.

Tubes 23 and 24 are connected together to constitute a symmetrical or locked electronic relay. That is, when either of tubes 23 and 24 is conducting the other tube is held non-conducting until the conductivity conditions are changed by application of a voltage pulse from a source outside the relay itself. As hereinafter used, the term "trip" means to change the conductivity from the tube that is initially conducting to the one that is initially non-conducting while the term "reset" refers to the reverse operation.

Tubes 23 and 24 are interconnected by resistor 25 and capacitor 26 in parallel between anode 27 and grid 28 and the similar connection of anode 29 to grid 30 through parallel connected resistor 31 and capacitor 32.

The gaseous discharge device 33 is connected in parallel with capacitor 34 to anode 27 through the resistor 35. When tube 23 is non-conducting the capacitor 34 is charged through resistor 35 to the breakdown potential of tube 33 and thereupon the tube 33 becomes conducting and discharges capacitor 34 with the production of a negative pulse that is transmitted over lead 36 and through capacitor 37 to the grid 38 of tube 24.

The operation of this system is as follows: Tube 4 is initially conducting due to the fact that key 22 is open, and tube 23 is also initially conducting. When key 22 is closed the unsymmetrical values of the circuits above described result in tube 5 becoming conductive while tube 4 is blocked by the potential drop across resistor 10 applied to grid 11. The resulting rise of potential on anode 6 is transmitted through lead 38a and capacitor 39 to the grid 40 of amplifier tube 41 which is biased to cutoff. However, when the positive pulse is impressed upon grid 40 the tube 41 becomes momentarily conductive and the resultant potential drop through anode resistor 42 is transmitted over lead 43 as a negative output pulse.

Simultaneously with the transmission of the positive pulse to grid 40 a negative pulse derived from the drop through resistor 10 is transmitted through capacitor 44 and lead 45 to grid 46 of tube 23, thus tripping this relay and causing tube 24 to become conductive. Capacitor 34 then charges up until the breakdown potential of tube 33 is reached when it discharges and a negative pulse is transmitted through lead 36 and capacitor

37 to grid 38 of tube 24 which resets this relay. When the conductivity is thrown from tube 24 back to tube 23 the potential on anode 29 rises to substantially supply voltage and a positive pulse is transmitted through lead 47 and capacitor 48 to the grid 49 of tube 50, causing tube 50 to become transiently conductive and thereby giving rise to a negative pulse in the common output 43. The time interval between the two negative pulses thus produced when the key 22 is closed may be controlled by the values of capacitor 34, resistor 35 and the potentials applied to the tube 33.

When key 22 is opened the potential on anode 1 rises to substantially supply voltage and a positive pulse is applied through lead 51 and capacitor 52 to grid 49 of tube 50 which causes a negative pulse in the output 43. It is thus apparent that with the system disclosed in Fig. 1 two pulses are transmitted when key 22 is closed and one pulse when key 22 is opened. It is of course understood that the output from 43 may be used in any manner known to the art to cause the radiation of pulse signals.

Fig. 2 depicts a different embodiment of my invention whereby three pulses are produced upon closing the key and two pulses when the key is opened. The tubes 4 and 5 and the circuit elements interconnecting the same are the same as the correspondingly designated parts in the unsymmetrical circuit portion of Fig. 1, and consequently they will not be described again in detail. Likewise, the gaseous conduction device 33, capacitor 34 and resistor 35 are structurally and functionally the same as the like numbered elements in Fig. 1.

However, in Fig. 2 there are two symmetrical relays 53 and 54 and in each relay either tube, after being made conductive, continues to conduct until interrupted by the application of a negative pulse from an outside source. Initially, tubes 4, 55 and 57 are conducting. When key 22 is closed a negative pulse is applied to grid 58 of tube 55 which trips the relay and blocks tube 55 while making tube 56 conductive. The rise of potential on anode 59 of tube 55 is transmitted through capacitor 60 to an amplifier that responds to positive pulses only and gives a negative pulse output, as above described in connection with tubes 41 and 50 in Fig. 1. Capacitor 34 then charges up and discharges through 33 which applies a negative pulse through capacitor 64 to grid 61 of tube 57 and trips the relay 54 with a resulting rise in positive potential on anode 62 of tube 57 that is transmitted through capacitor 63 to the output amplifier.

Tube 55 being still non-conducting, the capacitor 34 charges again and upon discharge through tube 33 a negative pulse is transmitted through capacitor 65 to grid 66 of tube 67 which resets relay 54 and throws conductivity back to tube 57. The resulting rise of potential on anode 68 is transmitted through capacitor 69 to the output amplifier. Simultaneously, the drop in potential on anode 62 when tube 57 is again rendered conducting transmits a negative pulse through capacitor 70 to grid 71 of tube 56 which resets relay 53, making tube 55 again conductive and preventing further charge of capacitor 34. It is thus seen that this apparatus gives rise to three pulses when key 22 is closed.

When key 22 in Fig. 2 is opened, tube 4 again conducts and the drop in potential on anode 6 thereof is transmitted as a negative pulse over lead 72 and capacitor 73 to the grid 58 of tube 55, thus tripping relay 53 and the same negative

5 pulse is transmitted through capacitor 14 to grid 61 of tube 57, thus tripping relay 54 also. There will be simultaneous positive pulses transmitted from tubes 55 and 57 through the respective capacitors 60 and 63, to the output amplifiers but since they are simultaneous they will give the effect of a single pulse from the output amplifier.

10 Tube 55 being thus non-conducting, capacitor 34 will charge and, upon discharge through tube 33 will apply a negative pulse through capacitor 65 to grid 66 of tube 67. This resets relay 54 and the drop in potential on anode 62 of tube 57 is transmitted through capacitor 70 to grid 71 of tube 56 which resets the relay 53 and prevents further charging of capacitor 34. When tube 67 is blocked by the negative pulse due to the discharge of capacitor 34, the rise of potential on anode 68 is transmitted as a positive pulse through capacitor 69 to the amplifier. It is thus seen that 15 two pulses are transmitted when key 22 in Fig. 2 is open.

20 It may be observed that grid 58 of tube 55 receives pulses from both plates of tubes 4 and 5 and that these pulses are of opposite polarity. However, in practice relay 53 will trip due to the 25 rise of a small grid leak to grid 58 and the fact that the output from tubes 4 and 5 is not balanced.

25 It will be obvious to those skilled in this art how additional symmetrical relays may be added to produce any desired number of pulses in the group at the beginning of a signal element and any different number of pulses in the group at the end of the signal element. The duration of the interval between the pulses marking the beginning of a signal element and the group denoting the end thereof is dependent entirely upon the time that the key 22 is kept closed.

30 Fig. 3 is a schematic showing of a receiver adapted to respond to signal elements defined by groups of pulses as above described. In particular, the circuit of Fig. 3 is adapted to receive communications transmitted by a system like that shown in Fig. 1, whereby two pulses are transmitted at the beginning of a signal element and one pulse at the end thereof. Relays 75 and 76 are of the symmetrical balanced circuit type above discussed. Grids 77 and 78 are respectively connected through capacitors 81 and 82 to the common input 83 and thus any negative pulse over input 83 will change the conductivity conditions in relay 75, blocking the tube that is conducting when the pulse is received and throwing conduction to the other tube in that relay. Initially tube 79 in relay 35 55 and tube 84 in relay 76 are conducting.

55 When the pair of pulses indicating the beginning of a signal element from the apparatus of Fig. 1 is received through input 83, the first negative pulse trips relay 75 and changes conductivity over to tube 86. Capacitor 85 does not reach the breakdown potential of tube 86 before the second pulse of the pair is received which is applied to grid 78 and resets relay 75. The rise in potential on anode 87 of tube 80 is transmitted as a positive pulse through capacitor 88 to the grid 89 of tube 90 which is biased to cutoff by voltage divider 91. This positive pulse causes tube 90 to become transiently conducting and the potential drop across anode 70 resistor 92 is applied as a negative pulse through capacitor 93 to grid 94 of tube 84 which trips relay 76 and causes tube 95 to become conductive.

75 The rise of potential on anode 96 of tube 84 is applied not only to grid 97 of tube 95 but

also to grid 98 of tube 99. It will be seen that when tube 84 is conducting the potential drop across anode resistor 100 will be applied to grid 97 of tube 95 and also, through lead 101 to grid 98 of tube 99, thus holding the tube 99 non-conductive and incapable of responding to an audio signal impressed on grid 98 through capacitor 102. However, when tube 84 is blocked the grid 98 of tube 99 rises to substantially the cathode potential and becomes conductive while relay 76 is tripped and thus makes perceptible in output 103 of tube 99 the audio signal impressed through capacitor 102. It is apparent that tube 99 will remain in operation during the interval between the two pulses marking the beginning of a signal element and the single pulse marking the end thereof, as will now be described.

When the single pulse denoting the end of a signal element is received it will trip relay 75, when was reset by the second pulse at the beginning of the signal element. This will start the capacitor 85 to charging and simultaneously the potential drop across anode resistor 104 will be applied through capacitor 105 and lead 106 to the grid 107 of tube 95 thus resetting relay 76, terminating the conductivity of tube 99 and ending the discernible signal output through capacitor 103. When capacitor 85 has reached the breakdown potential of tube 86 it will discharge through tube 86 and apply a negative pulse through capacitor 108 to grid 78 of tube 80 and reset relay 75. Likewise, the negative pulse will be transmitted through capacitor 109 to grid 89 of tube 90 and will neutralize the positive pulse applied to grid 89 through capacitor 88 due to the rise in potential of anode 87. This neutralization of the positive potential applied to grid 89 is necessary to prevent tube 90 from becoming conductive and tripping relay 76.

It will be apparent that additional balanced relays may be added to respond to any selected number of pulses at the beginning of a signal element and at the end thereof. It is evident that the time of charging of capacitor 85 must be greater than the time between two successive pulses in a group to prevent resetting of relay 76 during reception of the first group of pulses, but it must be less than the time between successive signal elements in order that relay 75 may be reset before the reception of the first pulse of a new group.

The invention herein described and claimed may be used and manufactured by or for the Government of the United States of America for governmental purposes without the payment of any royalties thereon or therefor.

I claim:

1. A pulse group system of communication, comprising an unsymmetrical relay including a first and a second tube each having an anode, a cathode and a grid; a common anode supply, a respective anode resistor connecting each said anode to said supply, grid returns including a respective grid resistor connected to each said grid, the said resistor connected to the grid of said second tube being at least substantially twice the value of the resistor connected to the grid of said first tube, a resistor and a capacitor in parallel connecting the grid of each tube to the anode of the other, a key connected between the cathode of said second tube and ground to control the current path through said unsymmetrical relay; a symmetrical relay including a third and

a fourth tube each having an anode, a cathode, and at least two grids, respective anode resistors connecting the anodes of said third and fourth tubes to said anode supply, a capacitor connecting the anode of said second tube to trip said symmetrical relay on closing of said key to a first grid of said third tube; a gaseous discharge device having an anode, a cathode and a grid, a timing resistor connecting the anode of said device to the anode of said third tube, a charging capacitor connected in parallel with said device to be charged on tripping of said symmetrical relay, a capacitor connecting a first grid of said fourth tube to a point between said timing resistor and the anode of said device to reset said relay on discharge of said capacitor through the gaseous discharge device; grid returns including a respective grid resistor connected to a second grid of each of said third and fourth tubes, a resistor and a capacitor in parallel connecting each said second grid to the anode of the other tube in the said symmetrical relay; two amplifier tubes each having an anode, a cathode and a grid, a common anode resistor connecting the anodes of said amplifiers to anode supply, means connecting the cathodes of said amplifiers in parallel, a capacitor connecting the grid of one said amplifier to the anode of said first tube to deliver a first pulse on closing said key, a respective capacitor connecting the grid of the other amplifier to the anode of said fourth tube to deliver a second pulse, when said symmetrical relay is reset and to the anode of said second tube to deliver a pulse when the key is released, and a common output connected to the anodes of both said amplifiers.

2. A pulse group system of communication, comprising an unsymmetrical relay including a first and a second tube each having an anode, a cathode and a grid; a common anode supply, a respective anode resistor connecting each said anode to said supply, grid returns including a respective grid resistor connected to each said grid, the said resistor connected to the grid of said second tube being at least substantially twice the value of the resistor connected to the grid of said first tube, a resistor and a capacitor in parallel connecting the grid of each tube to the anode of the other, a key connected between the cathode of said second tube and ground; a symmetrical relay including a third and a fourth tube, means interconnecting said third and fourth tubes whereby when one is conducting the other is held non-conducting, means to apply to said third tube pulses of potential due to changes in the anode potential of said second tube to trip said symmetrical relay on closing of said key; a gaseous discharge device having an anode, a cathode and a grid, a capacitor connected in parallel with said device to be charged on tripping of said symmetrical relay, a timing resistor connecting the anode of said device to said third tube to charge the capacitor in parallel with said device when said third tube is non-conducting, means to apply to said fourth tube a negative pulse arising from discharge of said capacitor through said device to reset said relay; two amplifier tubes each having an anode, a cathode and a grid, a common anode resistor connecting the anodes of said amplifiers to anode supply, means connecting the cathodes of said amplifiers in parallel, a capacitor connecting the grid of one said amplifier to the anode of said first tube to deliver a first pulse on closing said key, a respec-

tive capacitor connecting the grid of the other amplifier to the anode of said fourth tube to deliver a second pulse, when said symmetrical relay is reset and to the anode of said second tube to deliver a pulse when the key is released, and a common output connected to the anodes of both said amplifiers.

3. A pulse group system of communication, comprising an unsymmetrical relay including a first and a second tube each having an anode, a cathode and a grid; a common anode supply, a key connected to break the circuit through said second tube when said key is open, means interconnecting said tubes and said supply whereby said first tube conducts when said key is open and said second tube alone conducts when said key is closed; a symmetrical relay including a third and a fourth tube each having an anode, a cathode, and at least two grids, respective anode resistors connecting the anodes of said third and fourth tubes to said anode supply, a capacitor connecting the anode of said second tube to a first grid of said third tube to trip said symmetrical relay on closing of said key; a gaseous discharge device having an anode, a cathode and a grid, a timing resistor connecting the anode of said device to the anode of said third tube, a capacitor connected in parallel with said device to be charged on tripping of said symmetrical relay, a capacitor connecting a first grid of said fourth tube to a point between said timing resistor and the anode of said device to reset said relay on discharge of said capacitor through the gaseous discharge device; grid returns including a respective grid resistor connected to a second grid of each of said third and fourth tubes, a resistor and a capacitor in parallel connecting each said second grid to the anode of the other tube in the said symmetrical relay; two amplifier tubes each having an anode, a cathode and a grid, a common anode resistor connecting the anodes of said amplifiers to anode supply, means connecting the cathodes of said amplifiers in parallel, a capacitor connecting the grid of one said amplifier to the anode of said first tube to deliver a first pulse on closing said key, a respective capacitor connecting the grid of the other amplifier to the anode of said fourth tube to deliver a second pulse, when said symmetrical relay is reset and to the anode of said second tube to deliver a pulse when the key is released, and a common output connected to the anodes of both said amplifiers.

4. A pulse group system of communication, comprising an unsymmetrical relay including a first and a second tube each having an anode, a cathode and a grid; a common anode supply, a respective anode resistor connecting each said anode to said supply, grid returns including a respective grid resistor connected to each said grid, the said resistor connected to the grid of said second tube being at least twice the value of the resistor connected to the grid of said first tube, a resistor and a capacitor in parallel connecting the grid of each tube to the anode of the other, a key connected between the cathode of said second tube and ground; a symmetrical relay including a third and a fourth tube each having an anode, a cathode, and at least two grids, respective anode resistors connecting the anodes of said third and fourth tubes to said anode supply, a capacitor connecting the anode of said second tube to a first grid of said third tube to trip said symmetrical relay on closing of said key; a gaseous discharge device having an

anode, a cathode and a grid, a timing resistor connecting the anode of said device to the anode of said third tube, a capacitor connected in parallel with said device to be charged on tripping of said symmetrical relay, a capacitor connecting a first grid of said fourth tube to a point between said timing resistor and the anode of said device to reset said relay on discharge of said capacitor through the gaseous discharge device; grid returns including a respective grid resistor connected to a second grid of each of said third and fourth tubes, a resistor and a capacitor in parallel connecting each said second grid to the anode of the other tube in the said symmetrical relay; and means controlled severally by said first, said second and said fourth tubes to produce a negative output pulse upon cessation of conduction through any one of said first, second or third tubes.

20 5. A pulse group system of communication, comprising a first relay having two unsymmetrical conductive paths whereby one of said paths will conduct in preference to the other when both are closed, means operable to open or close said one path, said other path being initially conducting and said one path open; a second relay having two symmetrical conducting paths including means whereby either is held non-conducting while the other is conducting until the conductivity condition is changed by an applied potential pulse; means to derive a negative pulse from said one path in said first relay when said one path begins to conduct and apply said negative pulse to a first path in said second relay, said first path in said second relay being initially conducting, to change conductivity to the second path in said second relay, means connected to said first path in said second relay to be automatically energized when said first path in said second relay is non-conducting to apply a negative potential to said second path in said second relay after a predetermined interval to change conductivity back to said first path in said second relay; and means connected to be energized to produce a voltage pulse when either path in said first relay or said second path in said second relay ceases to conduct.

6. A pulse group system of communication, comprising two unsymmetrical conductive paths whereof one is initially open-circuited, the unbalance being such that said one path becomes conducting when the circuit is closed, including means in each path to produce a negative pulse at initiation of conduction in either path; first and second locked relays each having two symmetrical conductive paths, each said symmetrical path including means to produce and apply a potential due to current flow to hold the other path in the same relay non-conducting, means connecting said one unsymmetrical path to trip said first relay when said one symmetrical path is closed; timed pulse-producing means connected to be operative while said first relay is tripped and connected to trip said second relay; then reset said second relay; means connecting said second relay to said first relay to reset said first relay when said second relay is reset, means connected to said first relay to produce a positive output pulse when said first relay is tripped, means connected to said second relay to produce a positive output pulse when said second relay is tripped and also when it is reset; means connected to trip both said relays when said one symmetrical path is re-opened, said timing pulse means then resetting both relays, means to pro-

duce a positive output pulse when said relays are both tripped and means to produce another positive output pulse when both said relays are reset.

7. A pulse group system of communication, comprising two unsymmetrical conductive paths whereof one is initially open-circuited, the unbalance being such that said one path becomes conducting when the circuit is closed, including means in each path to produce a pulse at initiation of conduction in either path; first and second locked relays each having two symmetrical conductive paths, each said symmetrical path including means to produce and apply a potential due to current flow to hold the other path in the same relay non-conducting, means connecting said one unsymmetrical path to trip said first relay when said one symmetrical path is closed; timed pulse-producing means connected to be operative while said first relay is tripped and connected to trip said second relay, then reset said second relay; means connecting said second relay to said first relay to reset said first relay when said second relay is reset, means connected to said first relay to produce an output pulse when said first relay is tripped, means connected to said second relay to produce an output pulse when said second relay is tripped and also when it is reset; means connected to trip both said relays when said one symmetrical path is re-opened, said timing pulse means then resetting both relays, means to produce an output pulse when said relays are both tripped and means to produce another output pulse when both said relays are reset.

8. A pulse group system of communication, comprising two unsymmetrical conductive paths whereof one is initially open-circuited, the unbalance being such that said one path becomes conducting when the circuit is closed, including means in each path to produce a negative pulse at initiation of conduction in either path; first and second locked relays each having two symmetrical conductive paths, each said symmetrical path including means to produce and apply a potential due to current flow to hold the other path in the same relay non-conducting, means connecting said one unsymmetrical path to trip said first relay when said one symmetrical path is closed; means connected to be operative while said first relay is tripped and connected to trip said second relay, then reset said second relay; means connecting said second relay to said first relay to reset said first relay when said second relay is reset, means connected to said first relay to produce an output pulse when said first relay is tripped, means connected to said second relay to produce an output pulse when said second relay is tripped and also when it is reset; means connected to trip both said relays when said one symmetrical path is re-opened, said means operative when said first relay is tripped then resetting both relays, means to produce an output pulse when said relays are both tripped and means to produce another output pulse when both said relays are reset.

9. A receiver responsive to groups of pulses, comprising first and second locked relays, each said relay including two tubes each of which has an anode, a cathode, and at least two grids; a common anode supply, a respective anode resistor connecting each said anode to said supply, a resistor and a capacitor in parallel connecting the anode of each said tube to one grid of the other tube in the same relay; a gaseous discharge device and a reset capacitor in parallel,

a timing resistor connecting said device and said reset capacitor to the anode of a first tube in said first relay to charge said capacitor when said relay is tripped; a tube having a grid, a cathode and an anode interposed between said relays, means to block said interposed tube, a resistor connecting the anode of said interposed tube to said supply, a capacitor coupling the anode of said interposed tube to another grid of the first tube of said second relay; a respective capacitor coupling the anode of the second tube in said first relay to the grid of said interposed tube and to another grid of the second tube in said second relay to trip said second relay, when said first relay is reset; an output tube having a cathode, a grid and an anode, a resistor connecting the anode of said output tube to said supply, means connecting the grid of said output tube to said one grid of the first tube in said second relay to hold said output tube non-conducting when the first tube in said second relay is conducting, means to apply to the grid of the output tube an audio signal of insufficient strength to render said output tube conducting when the first tube of the second relay is conducting, an output lead coupled to the anode of said output tube; an input circuit coupled to another grid of each tube in said first relay, and means coupling said reset capacitor to the grid of said interposed tube and to another grid in the second tube of said first relay to reset said first relay, which resets said second relay and terminates the audio output.

10. A pulse group system of communication, comprising means as set forth in claim 5 in combination with receiving means which comprises first and second locked relays each having two symmetrical conductive paths, each said path including means to produce and apply a potential due to current flow to hold the other path in the same relay non-conducting, input means connected to said first relay to trip or to reset said first relay, depending upon which path is conducting; timed pulse producing means connected to one path in said first relay to be operative while said first relay is tripped, means controlled by the second path in said first relay to trip said second relay when said first relay is reset, signal output means controlled by said second relay to operate while said second relay is tripped, and means connecting the second path in said first relay with the second path in said second relay whereby when said first relay is tripped by a pulse while said signal output is operating a reset pulse will be applied from said second path of said first relay to reset said second relay and thereafter said timed pulse means functions to reset said first relay.

11. In a pulse group system of communication, receiving means comprising first and second locked relays each having two symmetrical conductive paths, each said path including means to produce and apply a potential due to current flow to hold the other path in the same relay non-conducting, input means connected to said first relay to trip or to reset said first relay, depending upon which path is conducting; timed pulse producing means connected to one path in said first relay to be operative while said first relay is tripped, means controlled by the second path in said first relay to trip said second relay when said first relay is reset, signal output means controlled by said second relay to operate while said second relay is tripped, and means connecting the second path in said first relay with the second path in said second relay.

whereby when said first relay is tripped by a pulse while said signal output is operating a reset pulse will be applied from said second path of said first relay to reset said second relay and thereafter said timed pulse means functions to reset said first relay.

12. Pulse group signalling means, comprising first and second interconnected and functionally dependent circuits, one said first or second circuits being initially open and the other conducting; third and fourth functionally dependent circuits interconnected to hold either third or fourth circuit non-conducting when the other conducts, one of said third or fourth circuits being initially conducting; means connecting said initially open first or second circuit to said initially conducting third or fourth circuit to change the conductivity condition in said third and fourth when said first or second initially open circuit is closed; means connected to said initially conducting third or fourth circuit to produce a pulse a predetermined time after interruption of conduction in said initially conducting third or fourth circuit and to apply such pulse to the initially non-conducting third or fourth circuit to change conductivity back to said initially conducting third or fourth circuit, and means connected to each of said first and second circuits and to said initially non-conducting third or fourth circuit to produce a pulse upon interruption of conductivity in any respective one of these three circuits.

13. A pulse group signalling system, comprising apparatus as set forth in claim 12 in combination with receiving means which comprises a first and a second pair of functionally dependent circuits, the circuits in each pair being interconnected to hold either circuit in a pair non-conducting when the interconnected circuit is conducting, one circuit in each pair being initially conducting; the other circuit in each pair being initially non-conducting, a timed pulse producing device connected across said one circuit in said first pair and to the other circuit in said first pair to change conductivity back to said one circuit when said one circuit in said first pair has been non-conducting for a predetermined time interval; common input means connected to both circuits in said first pair whereby a negative pulse on said input will change conductivity from the then conducting circuit to the then non-conducting circuit; means connected to said other circuit in said first pair to produce a negative pulse and apply the same to said one circuit in said second pair when conduction in said other circuit of said first pair is interrupted, means connected to said other circuit in said first pair to apply a negative pulse to said other circuit in said second pair to be held conducting only when said one circuit in said second pair is non-conducting, an output connection to said tube, and means to apply an audio signal to said tube to appear in said output only when said tube is held conducting as aforesaid.

14. Pulse group signal receiving means, comprising a first and a second pair of functionally dependent circuits, the circuits in each pair being interconnected to hold either circuit in a pair non-conducting when the interconnected circuit is conducting, one circuit in each pair being initially conducting; a timed pulse producing device connected across said one circuit in said first pair and to the other circuit in said first

pair to reset said first pair when said first pair has been tripped for a predetermined time interval; common input means connected to both circuits in said first pair whereby a negative pulse on said input will change conductivity from the then conducting circuit to the then non-conducting circuit; means connected to said other circuit in said first pair to produce a negative pulse and apply the same to said one circuit in said second pair when conduction in said other circuit of said first pair is interrupted, means connected to said other circuit in said first pair to apply a negative pulse to said other circuit in said second pair when conduction is initiated in said other circuit of said first pair; an output tube connected to said one circuit in said second pair to be held conducting only when said one circuit in said second pair is non-conducting, an output connection to said tube, and means to apply an audio signal to said tube to appear in said output only when said tube is held conducting as aforesaid.

15. Pulse group signal receiving means, comprising a first and a second pair of functionally dependent circuits, the circuits in each pair being interconnected to hold either circuit in a pair non-conducting when the interconnected circuit is conducting, one circuit in each pair being initially conducting; means to reset said first pair when said first pair has been tripped for a predetermined time interval; common input means connected to both circuits in said first pair whereby a negative pulse on said input will change conductivity from the then conducting circuit to the then non-conducting circuit; means connected to said other circuit in said first pair to produce a negative pulse and apply the same to trip said second pair when conduction in said other circuit of said first pair is interrupted; means connected to said other circuit in said first pair to apply a negative pulse to reset said second pair when conduction is initiated in said other circuit of said first pair; and means connected to said second pair to produce a discernible output signal only when said second pair is tripped.

16. Apparatus as set forth in claim 12, in combination with receiving means responsive to a pair of received pulses to initiate a discernible signal and to a single pulse to terminate said signal.

17. Apparatus as set forth in claim 12, in combination with receiving means responsive to a predetermined number of received pulses to initiate a discernible signal and to a number of subsequently received pulses to terminate said signal.

18. A receiver responsive to pulsed signals including two relays, a timer responsive to tripping of the first relay, the second relay being tripped responsively to the resetting of the first relay, an input circuit to the first relay operative to trip and reset the same on a pulsed signal and thereby trip the second relay, and operative on a subsequent pulsed signal to trip said first relay, said timer subsequently resetting said second relay and means coupling to said first relay to reset the same responsively to resetting the second relay.

19. A receiver as set forth in claim 18 further including an audio channel, and means for delivering an audio signal to said channel controlled by said second relay to be operative while said second relay is in tripped condition.

20. In a communication system of the mark-space type wherein the leading and trailing edges

of the mark signals are delineated by first and second signal components respectively, signal receiving means responsive to a first received signal to initiate a discernible signal and to a subsequently received second signal to terminate the discernible signal, one of the received signals comprising a group of impulses, and the other of said signals comprising a different number of impulses.

21. In a communication system of the mark-space type wherein the leading and trailing edges of the mark signals are delineated by first and second signal components respectively, signal receiving means responsive to a first received signal to initiate a discernible signal and to a subsequently received second signal to terminate the discernible signal, one of the received signals comprising a single impulse, and the other of said signals comprising a group of impulses.

22. In a pulse signal communication system, transmitting apparatus comprising, in combination, a pulse generator, a switch, and circuit means controlling said impulse generator responsive to the opening of said switch to effect generation of a first pulsed signal and responsive to the closing of said switch to generate a second pulsed signal including a different number of pulses from the first pulsed signal.

23. A transmission system comprising a pulse generator, a switch, circuit means controlling said impulse generator responsive to the closing of said switch to effect generation of a first pulsed signal and responsive to the opening of the switch to generate a second pulsed signal having a characteristics difference from the first pulsed signal, and receiver means receiving said pulsed signals responsive to one of said pulsed signals to initiate a discernible signal and responsive to the other of said signals to terminate the discernible signal.

24. In combination, a trigger circuit having a stable condition and an unstable condition and comprising a pair of vacuum tubes, a condenser connected between the grid of one tube and the anode of the other tube, a condenser shunted by a resistor connected between the anode of said one tube and the grid of said other tube, means connected to said trigger circuit for normally maintaining conduction in one of said tubes and non-conduction in the other, a second trigger circuit having two states of stability and including a pair of vacuum tubes, similar coupling networks connecting the grid of each tube of the second trigger circuit to the anode of the other, a coupling circuit capable of passing pulses of only one polarity connecting the two trigger circuits in cascade relation, coupling means between the second tube of said second trigger circuit and the second tube of the first trigger circuit and means for applying initiating voltage pulse to the first trigger circuit of such polarity and magnitude as to change the condition of the first trigger circuit.

25. In combination, first and second trigger circuits each having a pair of vacuum tubes, connections cross-coupling the grids and anodes of the tubes of each trigger circuit, means connected to the first trigger circuit for endowing the same with a stable state and an unstable state, a differentiator circuit of a reactance and a resistor in series coupled between one of the anodes of the first trigger circuit and ground, a coupling vacuum tube having its grid connected to the junction of said reactance and resistor and having its anode coupled to the grid of one of the

tubes of said second trigger circuit, means for biasing said coupling vacuum tube to cut off during the stable condition of said first trigger circuit, coupling means between the second tube of said second trigger circuit and the second tube of the first trigger circuit and means for deriving from said second trigger circuit a voltage developed thereby.

26. In combination, first and second vacuum tube trigger circuits for producing flat top pulses, means connected to the first trigger circuit for endowing the same with a stable state and an unstable state, a connection for applying an initiating voltage pulse signal to said first trigger circuit of such polarity and magnitude as to change the condition of said first trigger circuit, and means coupling said trigger circuits together in such manner that there is introduced a time lag between the time of occurrence of said initiating pulse and the operation of said second trigger circuit, said means including a condenser and a vacuum tube in series therewith, said vacuum tube being biased to pass pulses of only one polarity and coupling means between the second tube of said second trigger circuit and the second tube of the first trigger circuit.

27. In a communication system of the type in which signal characteristics are represented by a series of first impulses modulated in duration to represent the signal characteristics; an arrangement for reducing the disturbing effects of interfering impulses comprising, means for producing from each of said first impulses a group of at least three short duration indicating impulses, at least two of said group of indicating impulses being spaced apart by a time interval which is short compared to the duration of the first impulses, the remaining impulses of said group being spaced from said two by an interval governed by the duration of said first impulses, receiver means for receiving said indicating impulses, and discriminator means in said receiver means for discriminating between impulse groups having a number and time spacing other than that produced by the first mentioned means.

28. A communication system according to claim 27 further comprising translator means for deriving the modulating signal from said received indicating impulses.

29. A method of communicating by continuous wave radio telegraphy signals of the mark-space type, comprising the steps of converting the mark signals into pulse signals of substantially constant duration and spaced in time corresponding to the duration of said mark signals, the pulse signals corresponding to the initiation of said mark signals being different in number from those corresponding to the termination thereof, transmitting said pulse signals through space, receiving said signals, and converting said pulse signals back to said mark signals thereby reproducing said telegraphy signals.

30. A method of communicating by continuous wave radio telegraphy signals of the mark-space type, comprising the steps of converting the mark signals into pulse signals comprising a pair of pulses corresponding to the initiation of said mark signals and a single pulse corresponding to the termination of said mark signals, transmitting said pulse signals through space, receiving said pulse signals, and converting said received pulse signals back to said mark signals thereby reproducing said telegraphy signals.

31. Apparatus for communicating by means of continuous wave radio telegraphy signals of the

mark-space type, comprising a gaseous discharge tube device to convert the mark signals into pulse signals of substantially constant duration and spaced in time corresponding to the duration of said mark signals, the pulse signals corresponding to the initiation of said mark signals being different in number from those corresponding to the termination thereof, means to transmit said pulse signals through space, means to receive said transmitted pulse signals, and a second discharge tube device to convert said pulse signals back to said mark signals thereby to reproduce said telegraphy signals.

32. Apparatus for communicating by means of continuous wave radio telegraphy signals of the mark-space type, comprising a gaseous discharge tube device to convert the mark signals into pulse signals comprising a pair of pulses corresponding to the initiation of the mark signals and a single pulse corresponding to the termination of said mark signals, means to transmit said pulse signals through space, means to receive said transmitted pulse signals, and a second discharge tube device to convert said pulse signals back to said mark signals thereby to reproduce said telegraphy signals.

33. A pulse generating means comprising first and second trigger circuits each having two conductive paths, means for normally maintaining conduction in a particular path of each of said trigger circuits, means for changing the state of conduction of said first trigger circuit, means for changing the state of conduction of said second trigger circuit, both of said trigger circuits being coupled to a common output signal channel to initiate therein output signal pulses upon changes in said states of conduction.

34. A pulse generating device comprising first and second trigger circuits each having two conductive paths, means for normally maintaining conduction in a particular path of each of said trigger circuits, means for changing the state of conduction of said first trigger circuit, means responsive to the changing of the state of conduction of said first trigger circuit for changing the state of conduction of said second trigger circuit, both of said trigger circuits being coupled to a common output signal channel to initiate therein output signal pulses upon changes in said states of conduction.

35. In combination, first, second and third trigger circuits each having first and second conductive paths, at least one input and one output means, means coupling an output means of said first trigger circuit to an input means of both of said second and third trigger circuits to thereby enable a change in the state of conduction of said first trigger circuit to affect the states of conduction of said second and third trigger cir-

cuits, and means coupling an output means of said third trigger circuit to an input means of said second trigger circuit to thereby enable a change in the state of conduction of said third trigger circuit to affect the state of condition of said second trigger circuit.

36. In a pulse signal communication system, transmitting apparatus comprising in combination, first means including a pulse generator for producing pulses for conveying intelligence, and a second means including a second pulse generator controlled by said first generator to produce pulse groups at the beginning and at the end of each of said intelligence conveying pulses, said beginning and said end pulse groups having different numbers of pulses therein.

37. In a communication system including the transmitting apparatus defined in claim 36, signal receiving means responsive to a received group of pulses to initiate a discernible signal and to a subsequently received groups of pulses to terminate said signal.

CLAUD E. CLEETON.
